PULLEY CLOTHESLINE AND HOLDER
THEREFOR

John Waldheim, Elizabeth, N. J.

Application October 11, 1941, Serial No. 415,420

24 Claims. (Cl. 211—119.02)

This invention relates to improvements in pulley clothes line and holders therefor, and is a continuation in part of my application Ser. No. 243,955, filed December 5, 1938, now Patent No. 2,292,415, dated August 11, 1942.

The ordinary pulley clothes line has two reaches namely a clothes carrying reach and an idle reach, these reaches move in opposite directions while the line is being operated. Frequently the articles of clothes become wrapped around both reaches of the line, by the wind, which hinders the operation of the line or in other words makes it difficult to draw in the clothes because of their rubbing action against the idle reach traveling in the opposite direction to that of the clothes carrying reach. The clothes also become objectionably soiled by such rubbing action.

Provision is made in the above mentioned patent of means including a guard reach to prevent the articles of clothes, if wrapped around the line, from hindering the operation of the line and from becoming soiled. In some forms of the invention illustrated in the above mentioned application the guard reach, the clothes carrying reach and the idle reach are composed of a single piece of rope.

The present invention relates more particularly to a clothes line in which a separate piece of rope may be used, with an already existing two reach pulley clothes line, to provide the guard reach. This will be understood is a feature of economy since it requires a minimum of new rope to produce the novel clothes line.

To this end the separate piece of rope, which in one form of the invention forms the guard reach, is arranged, supported and connected to travel in the same direction as the clothes carrying reach. In all forms of the invention herein illustrated, the guard reach is disposed above the idle reach so that in case the articles of clothes become wrapped around the clothes line they are caused to lie on the guard reach to be held thereby from bearing on the idle reach so that said idle reach may move freely in a direction opposite to the guard reach without interfering with or hindrance by the clothes, thus making it possible to readily operate the clothes line to pull in the line with the clothes wrapped around it and without soiling the clothes.

Features of the invention also relate to devices used with the novel clothes line to hold the reaches thereof in proper relation and definitely spaced from each other.

In the drawings which form part of the speci-

fication Fig. 1 is a side elevation of a clothes line having only three reaches;

Fig. 2 is a view similar to Fig. 1 but shows the lower reach shifted to its clothes supporting position and a plurality of holders attached to the line;

Fig. 3 shows one end of a clothes line similar to that shown in Fig. 1 but illustrating another method of attaching one end of the guard reach;

10 Figs. 4 and 5 are views similar to Figs. 1 and 2 and show a modified form of clothes line;

Fig. 6 is a side elevation of the clothes line showing another method of attaching the guard reach thereto;

15 Figs. 7, 8 and 9 are modified forms of the invention shown in Figs. 3, 5 and 6, respectively, and in which the additional piece of rope forms the lower reach to which the articles of clothes are attached while hanging them on the line;

20 Figs. 10, 11 and 12 are front, end and plan views, respectively, of one form of holder which may be used with the various forms of clothes lines, to support one end of the guard reach;

Figs. 13 and 14 are front and plan views, respectively, of a detachable holder which may be used on the various forms of clothes lines to support intermediate portions of the guard reach;

25 Fig. 15 is an end view of the upper portion of the holder shown in Fig. 13;

30 Fig. 16 is an elevation of a clamp for securing one end of the guard reach in the form of clothes line shown in Figs. 1 and 2;

Fig. 17 is a vertical section taken on the line 17—17 of Fig. 16;

35 Fig. 18 is an elevation of a portion of a three reach clothes line with another type of holder for supporting one end of the guard reach;

Fig. 19 is a top plan view of the upper end of the holder shown in Fig. 18;

40 Fig. 20 is a bottom plan view of the holder shown in Fig. 18; and

Fig. 21 is a vertical section taken on the line 21—21 of Fig. 18.

Similar reference characters represent similar parts throughout the specification.

In Fig. 1 the entire clothes line is designated by the reference character 29d. It consists of an elongated loop supported by pulleys, 90 and 90d, the pulley 90 being located at the clothes attaching station and the pulley 90d being located remote therefrom. The loop forms a lower reach 34d to which the articles of clothes, not shown, may be attached and an idle or return reach 35d which is located above the clothes supporting reach 34d.

To tighten or slacken the reaches 34d and 35d there is provided in one end of the rope constituting said reaches, a loop 50d through which the other end 51d of the rope may be slipped freely while pulling on it to tighten the line, and by permitting the end to pass through said loop in a reverse direction to slacken or loosen the line reaches. A suitable knot 52d may be made to prevent accidental slipping of the end 51 through the loop 50d the portion of the rope pulled through the loop 50d may be formed into a bundle 52 in the usual manner and supported on the reach 34d. The portion of the line thus far described is like an ordinary two reach clothes line.

To apply the invention to an already existing two reach pulley clothes line, like the one above described, and thus keeping at a minimum the cost of material required to provide the novel clothes line, there is provided, see Figs. 1 and 2 a separate piece of rope 89. In this form of the invention the separate piece of rope forms a guard reach 37d which is connected, at its opposite ends, to the loop of the already existing two reach pulley line and may be attached thereto by securing one end thereof to a specially formed loop 91 in the lower reach 34d, the loop 91 being formed far enough from the loop 50d to never pass through the latter loop while tightening the reaches of the line 39d. The piece of line 89 extends from said loop through a holder 92, indicated diagrammatically in Figs. 1 and 2 but is shown clearly in Figs. 10, 11 and 12 and which is secured to the clothes supporting reach 34d, in a manner hereinafter described. The rope 89 then extends from the upper part of the holder or bracket 92 to a pulley 39d which may, if desired, be supported at the clothes attaching station, by a separate bracket independent of the pulley 90. The rope 89 passes over and around the pulley 39d and extends to the opposite end of the clothes line 29d where it may be secured to reach 35d by a clamp 93 illustrated in Figs. 16 and 17 and hereinafter described. It will readily be understood that since the end of the separate piece of rope 89 is secured to the elongated loop at opposite sides of the tightening means that the reach formed by the rope 89 is also tightened and slackened together with reaches 34d and 35d.

It should be understood that the piece of rope 89, constituting the guard reach 37d, may also be applied to the line, if desired, by first attaching it by means of the clamp 93, then passing it around the pulley 39d, then to the bracket 92 and then attaching it to the loop 91. In any event the reaches 34d and 35d are first tightened by means of the loop 50d and knot 52d before securing the last end of the rope 89. Thus the guard reach or section 37d, which remains permanently attached as part of the line 29d, is readily loosened or tightened simultaneously with the other reaches 34d and 35d.

Instead of the loop 50d, in the lower reach 34d, which forms part of the means for loosening or tightening all the line reaches, there may be provided a loop 50e, Fig. 3, in which said loop 50e and that end of rope which slides through it are arranged in reverse order to that shown in Fig. 1 and the end of the rope 89 may be secured directly to the loop 50e. In this arrangement the formation of a special loop 91, such as shown in Fig. 1, is avoided and the end of the rope 89 is attached to the clothes carrying reach 34d by means of loop 91 or 50e. The other end of the rope 89 may be secured to the reach 34d by means of a

clamp similar to the one, 93, shown in Fig. 16.

As the attaching of the clothes progresses at the left hand end of the line, Fig. 1, the holder 92 advances towards the pulley 90d at the other end of the line and the length of the guard reach 37d gradually increases, and it moves in the same direction as the lower or clothes supporting reach 34d, but in a direction opposite to that in which the intermediate reach moves. At intervals holders 85 are attached to the line to maintain all of the reaches definitely spaced from each other. Thus if the articles of clothes blow over the line 29d they lie on the upper or guard reach 37d which, assisted by the holders 85 and 92, keeps the clothes from dragging over or rubbing against the intermediate reach 35d.

Only one holder 92, such as illustrated in Figs. 10, 11 and 12, is used on the clothes line shown in Figs. 1 and 2. This holder is in some respects like the holder 85 shown in Fig. 13 and herein-after described. The holder 92 is provided at its lower end with securing means 61d in the form of a clamp comprising a fixed jaw 95, formed integral with the body part 56d, and a jaw 96 of a moveable plate 96d. The body-part 56d of the holder has a horizontal groove 97 in which a lip 98 of the jaw 96 engages, and about which the jaw 96 may be swung to adjust it properly to the other jaw 95 to grip or release the reach 34d.

The clamp 61d may be operated, to grip the reach 34d tightly, by means of a thumb screw 99 having a shank 100 which extends freely through the jaw plate 96d and is threaded into the body part 56d. The free end of the shank 100 is provided with an annular rib 101 to prevent detachment of the clamp plate 96d and thumb screw 100 and thus prevent loss of the plate and screw. The jaw 95 may be knurled at 102, and also the jaw 96, to assist in gripping the reach 34d.

The holder 92 is provided, at its upper end, with securing means 62d comprising two outer fingers 103 and an intermediate finger 104. The finger 104 is offset with respect to the other fingers 103 to form a bight 104d, in the line portion 89, as shown in Fig. 12. Thus the upper end of the holder 92 is held firmly and kept from shifting leftwardly, at its upper end, in Figs. 2 and 10. The reach 37d tends to pull the upper end of the holder 92 leftwardly in Figs. 1 and 2 but such movement of the holder is objectionable and is prevented by the short piece of rope 89 extending diagonally downward from the holder 92 to the loop 91, said short piece of rope being secured to the upper end of holder 92 and to loop 91. The holder 92 is also provided with a roller 58d which is supported on a spindle 57d and runs on reach 35d. A guard finger 71d on the holder 92 cooperates with the flange 60d of the roller 58d to prevent accidental detachment of the holder from the reaches 35d and 36d. Lips 87d and 88d are provided at the opposite side edges of the body part 56d and extend diagonally rearward therefrom to facilitate the passage of the clamp 93 through the holder 92.

The holder 85 is illustrated in detail in Figs. 13, 14 and 15. As previously stated it is similar to the holder 92, shown in Figs. 10, 11 and 12, since it is provided with a roller 58c supported by a headed spindle 57c secured to the body part 56c and because the body part is provided with lips 87 and 88 to facilitate passage of the clamp 93 through said holder.

The holder 85 is provided at its lower end with gripping means 61c for demountably attaching it

to the reach 34d so that the holder will travel with said reach. This means comprises hook-like means 61c having two up-turned hooks 63c which extend to one side of the body part 56c so that the reach 34d may readily be inserted into the hook-like means from one side of the holder. The hooks 63c are angularly disposed with reference to each other so as to form a bight in the reach 34d to thereby grip said reach tightly and cause the holder to travel with it.

There are provided two obstructing or guard members 67c, one on each hook 63c. These guard members 67c extend diagonally over the reach 34d to prevent accidental removal of the reach 34c from the hooks 63c and thus prevent accidental detachment of the holder from the line. The lower edges of guard members 67c cooperate with the reach 34d in maintaining the holder 56c substantially vertical to the line.

The means 62c at the upper end of the holder 85 which engages said upper or guard reach 37d does not grip the reach tightly but permits freedom of movement between the holder and the reach 37d. The means 62c includes a hook 63c in which the reach 37 engages, said hook being formed at the upper end of a narrow portion 86 of the body part 56c. The hook 63c is provided at its free end with guard members 71c which extend diagonally rearward under the reach 37c and cooperate with the narrow portion 86 of the body part to prevent accidental detachment of the holder from the guard reach 37c. Thus it is impossible to remove the reach, while in straight condition, from the hook 63c. In order to remove it, it is necessary to angularly dispose the reach and holder with reference to each other, as viewed from the top, Fig. 14, until the reach 37d clears the free end of the one of the members 71c whence the reach may be moved downwardly at one side of the holder, out of the hook 63c. This operation is then repeated at the opposite side of the holder to completely remove the reach 37d from said holder.

The intermediate reach 35, is protected against accidental detachment from the holder 85, by the guard finger 71c which extends upwardly into overlapping relation with the flange 60c of the roller 58c as viewed from the right hand side of Fig. 13. The finger 71c forms with the roller flange 50c a diagonally-disposed passage way or slot 59c through which the intermediate reaches may be passed, for the purpose of attaching or detaching the holder, only when it and the intermediate reach are diagonally disposed with respect to each other in a vertical plane in which the clothes line is disposed.

The lower edges of the members 67c of the gripping means 61c of the holder 85 cooperate with the reach 34d, which is taut, to maintain the holder 85 in a substantially vertical position and thus prevent accidental movement of the holder to a position in which the reach 35d may pass through the slot 59c. In this manner accidental detachment of the holder 85 from the reach 35d is prevented.

The clamp 93, by which the end of the additional piece 89 of rope is secured to the reach 35d, is clearly illustrated in Figs. 16 and 17. It is composed of two oppositely disposed plates 105 and 106 each having knurled grooves 107 and 108 to embrace the reach 35d and the end of rope or line section 89. Said plates may be drawn together by screws 109 to tightly grip the rope 89 and reach 35d, the shanks of said screws passing

freely through the plate 105 and being threaded into the other plate 106.

To further facilitate the passage of the clamp 93 through the holder 85 and 92 there is provided on one of its plates 105, 106 an inclined tail 110 which readily guides the clamp 93 under the rollers 58c and 58d when the clamp passes the rollers from the left side in Figs. 10 and 13. To further facilitate passage of the clamp 93 through said holders 10 the opposite edges of each plate 105 and 106 are also provided with projections 111 which are bent diagonally from each plate, projections on the plate 105 extending towards those on the plate 106. The edge portions, of each of the plates 105 15 and 106, above and below the projections 111 are rounded to aid in free passage of the clamp 93 through the holder 92.

A different form of holder, 115, illustrated in Figs. 19 to 21 inclusive, may be used instead of the 20 holder 92 of Fig. 10. This holder 115, is provided at its upper end with an aperture 116 for the purpose of securing thereto one end of the rope 87, of which the reach 37d is composed, instead of to the lower reach 34d as shown in Fig. 1. A roller 58f rides on the intermediate reach 35d and rotates on a spindle 57f secured to the body part 56f of said holder. The flange 60f of said roller cooperates with a guard finger 71f to prevent accidental detachment of the holder from the reach 35d. The holder is secured to the lower reach 34d by means of a clamp 61f which is similar to the clamp 61d except that the jaws 95f and 96f are held together by machine screws 99f instead of the thumb screw 99.

35 Since the end of the rope 89 is not secured to the reach 35d as in Figs. 1 and 2 there is also a tendency of the guard reach 37d, in this form of the invention, to pull the upper end of the holder 115 leftwardly in Figs. 6 and 18. This tendency is

40 counteracted by an arm 117 extending from one side of the holder and along the reach 34d to which the distant end of said arm may be attached in any suitable manner. As herein illustrated the arm 117 is L-shaped in cross-section, Fig. 21, and forms at one end, part of a clamp jaw 95f. To facilitate attachment to the reach 34d, the arm is provided with an elongated slot 118 through which the reach 34d extends diagonally as shown in Fig. 20, the reach 34 being insertable into said slot through a narrow passage 119.

45 Thus it will be understood that as the guard reach 37d pulls leftwardly on the upper end of the holder 115 the distal or free end of the arm 117 is pressed downwardly against the reach 34d and 50 counteracts the action of the guard reach. Thus the holder 115 is maintained in a substantially vertical position by the arm 117 acting against the reach 34d. It will be understood from Fig. 18 that the slot 118 and narrow passage 119 form 55 guard members 119x to prevent accidental detachment of the free end of the arm 117 from the reach 34d. The application of the holder 115 to the novel pulley clothes line is illustrated in Fig. 6.

60 From the foregoing it will be understood that by the addition to an ordinary two reach pulley clothes line, of a separate piece 89 of line, an extra pulley 39d and a holder such as 92 or 115, there is provided a three reach clothes line including a guard reach 37d to prevent the clothes from rubbing on the idle reach 35d of the clothes line, and 65 that in the event that the clothes line is long additional holders 85 may be attached thereto, as shown in Fig. 2, as the operation of the line proceeds in the hanging out of the clothes.

70 By employing a longer portion of rope 89g, as 75

shown on the clothes line 29g, illustrated in Figs. 4 and 5 the use of clamp 93 such as used on the clothes line 29d, Fig. 1, may be avoided, and detachable holders 85g and 92g may be used, these holders being like the holders 85 and 92 except that the guide members 87, 88 and 87d, 88d are not used. In this form of clothes line the extra portion 89 of rope which forms the guard reach 31g, is long enough to extend around the pulley 90d, at the right in Figs. 4 and 5, in all possible positions of the clothes line and the ends of the portion 89g never passes any of the holders 85g and 92g.

Thus the clothes line 29g, has four reaches 34g, 35g, 36g and 37g, two of the reaches 34g and 35g constituting the two reaches of an ordinary clothes line, the two additional reaches 36g and 37g, being provided by means of the separate piece 89g of rope which is supplied principally to form the guard reach 31g to prevent the clothes from rubbing against the intermediate reaches 35g and 36g which travel in a direction opposite to the clothes supporting reach 34g and the guard reach 37g.

The forms of the invention illustrated in Figs. 7, 8 and 9 are modifications of those illustrated in Figs. 3, 5 and 6 respectively. The line 29x of Fig. 7 differs from the line 29d of Fig. 2 in that the extra piece 89x of rope forms the lowermost or clothes supporting reach 34d and the upper reach of the elongated loop forms the guard reach 31dx. The means including the loop 50dx by which the reaches of line 29x may be tightened or loosened is provided in the upper reach 31dx, and the loop 91x to which the end of the additional piece 89x of rope is secured is also formed in the upper reach 31dx.

Similarly the clothes lines 29y and 29z, Figs. 8 and 9, differ from the clothes lines 29g and 29e, Figs. 5 and 6, respectively, in that the separate pieces 89y and 89z of rope provide the clothes carrying reaches 34gy and 34dz respectively, and the upper reaches 31dy and 31dz of the elongated loops serve as guard reaches.

It will be understood that light articles of clothes such as handkerchiefs may be hung on uppermost reaches of the lines, in all forms illustrated, the heavier pieces being hung on the lowermost reach.

While certain preferred embodiments of the invention have been described, it will be understood that certain parts may be used with others and that changes in the form, arrangement, proportions, sizes and details thereof may be made without departing from the scope of the invention as defined in the appended claims.

I claim:

1. In a pulley clothes line, the combination of an elongated loop of rope having two parallel reaches, pulleys, one at each end of said loop, to guide said reaches in a vertical plane to travel in opposite directions, separate means and, means to support said separate means to form a third reach coextensive with the other two reaches and in the same plane as the other two reaches, said reaches being arranged with respect to each other so that one of the loop reaches and the third reach form outer reaches, the other loop reach being arranged intermediate between said outer reaches, the supporting means including means to cause the third reach to travel simultaneously with and in the same direction as the other outer reach, the lowermost outer reach serving as a clothes carrying reach, the uppermost outer reach serving as

a guard reach to prevent the articles of clothes when blown over the pulley line from lying on the intermediate reach.

2. In a pulley clothes line, the combination of two reaches, formed of a single piece of rope, two pulleys to guide said reaches to travel in a vertical plane in opposite directions and form an elongated loop, one of said pulleys being located near a clothes attaching station, the other pulley being located remote from said station, one of the loop reaches forming an outer reach, the other loop reach forming an intermediate reach, a separate piece of material to form a third reach, one end of the third reach being secured to said loop, said end being located close to said station, said third reach extending to the remote pulley and being attached at its other end to said loop, said third reach forming an outer reach, one of the outer reaches serving as a clothes supporting reach being located substantially in the same vertical plane as the intermediate reach and, the other outer reach serving as a guard reach to prevent the articles of clothes when blown over the pulley line from lying on the intermediate reach which travels in a direction opposite to the direction of travel of the other two reaches, a separate pulley located at the clothes attaching station to guide one end of the third reach, and a device to guide the other end of the third reach, said device including means to secure it to one of the outer reaches, means to guide it on the idle reach, and means to attach it to the other outer reach.

3. In a pulley clothes line, the combination of a loop having two reaches formed of a single piece of material, two pulleys to guide said reaches to travel in opposite directions, one of said pulleys being located near a clothes attaching station, the other pulley being located remote from said station, a separate piece of rope to form a third reach, both ends of the separate piece of rope being secured to said loop, the major portion of the separate piece of rope extending along said loop, a separate pulley located at the station end of the pulley line to guide one end of the third reach, and a device secured to the clothes carrying reach to guide the other end of the said third reach, said device including means to guide it on one of the loop reaches, and means to attach said device to said third reach, all of said reaches being located substantially in the same vertical plane.

4. In a pulley clothes line, the combination of a piece of rope in the form of an elongated loop constituting an upper reach and a lower reach, pulleys, one at a clothes attaching station, and one remote from said station, said pulleys supporting the loop so that the reaches travel in opposite directions, a third reach connected at one end to said loop, a separate pulley at said station to support and guide one end of said third reach, a device supported by and secured to one of the loop reaches to support and guide the other end of the third reach which is connected to said device, means to guide said device on the other one of the loop reaches, and means extending from said device to engage the loop reach to which said device is secured to counteract a pull exerted on one end of said device by said third reach and thus maintain said device in a substantially vertical position on the pulley line.

5. In a pulley clothes line, the combination of a single piece of rope, means to connect the ends

of said rope to form a loop, pulleys, one at a clothes attaching station, and one remote from said station, said pulleys supporting said loop to form two reaches to travel in opposite directions, the connecting means being also effective to tighten or slacken said reaches, separate means to form a third reach coextensive with the other reaches, means to support said third reach, and means for securing said third reach to the loop so that it may travel with one of the loop reaches and so that the third reach may be tightened or slackened simultaneously with the other reaches, said reaches being arranged in superposed relation in the same plane and constituting two outer reaches and an intermediate reach, the outer reaches travelling in the same direction and opposite to the direction of travel of the intermediate reach, one of said outer reaches serving as a clothes supporting reach, the other outer reach serving as a guard reach to keep the clothes from lying on the intermediate reach when the clothes become lodged over the pulley line.

6. In a pulley clothes line, the combination of a single piece of rope, means to connect the ends of said rope to form a loop, pulleys, one at a clothes attaching station and one remote from said station, said pulleys supporting the loop to provide two reaches to travel in opposite directions, the connecting means being also effective to tighten or slacken said reaches, a separate piece of rope to form a third reach coextensive with the other reaches, means to support said third reach, the supporting means including a pulley at said station, and a device connected to one of the loop reaches, and means for securing the ends of said separate piece of rope to the loop at opposite sides of the connecting means so that the third reach may also be tightened or slackened simultaneously with the two loop reaches, said reaches being arranged in superposed relation and constituting two outer reaches and an intermediate reach, said device having guiding means to cooperate with the intermediate reach, the outer reaches travelling in the same direction and opposite to the direction of travel of the intermediate reach, one of said outer reaches serving as a clothes supporting reach, the other outer reach serving as a guard to keep the clothes from lying on the intermediate reach when the clothes become lodged upon the pulley line.

7. In a pulley clothes line, the combination of a piece of line in the form of an elongated loop constituting two reaches arranged one above the other, pulleys, one at a clothes attaching station, and one remote from said station, said pulleys supporting the loop so that the reaches travel in opposite directions, a separate piece of rope to form a third reach coextensive with the other reaches and arranged in the same plane as the other reaches, a separate pulley at said station to support one end of said third reach, a device secured to and supported by one loop reach to support the other end of said third reach, means for attaching one end of said separate piece of rope to one of the reaches of said loop, means for attaching the other end of said separate piece of rope to said device, said separate piece of rope having a tendency to pull said device from its effective position, and a portion of said separate piece of rope extending from said device to the reach to which said device is attached to hold said device in its effective position against the pulling action thereon by the major portion of said separate piece of rope.

8. In a pulley clothes line, the combination 75

of a piece of rope in the form of an elongated loop constituting two reaches arranged one above the other, pulleys, one at a clothes attaching station, and one remote from said station, said pulleys supporting the loop so that the reaches travel in opposite directions, a separate piece of rope to form a third reach coextensive with the other reaches and arranged in the same plane as the other reaches, means to support said third reach so that it may travel with and in the same direction as one of the other reaches, the supporting means including a separate pulley at said station, and two devices supported on and at different positions lengthwise of one of the loop reaches, one end of the separate piece of rope being attached to one of the loop reaches and extending around said separate pulley, the other end of said separate piece of rope being attached to the device farthest from said station, means 10 to attach the last mentioned device to the reach upon which it is supported to prevent movement by the third reach of said device lengthwise of its supporting reach, and means to resist a tendency produced by said third reach to pull on the end of said device to which the third reach is attached, the device located between said separate pulley and the other device being effective to hold said reaches definitely spaced from each other.

9. In a pulley clothes line, the combination of a single piece of rope, means to connect the ends of said rope to form a loop, pulleys, one at a clothes attaching station, and one remote from said station, said pulleys supporting the loop to 15 form two reaches to travel in opposite directions, said reaches being disposed one above the other, the lower reach constituting a clothes carrying reach, the upper reach being an idle reach, the connecting means being also effective to tighten or slacken said reaches, a separate piece of rope to form a third reach, said third reach being coextensive with the other reaches and located above the idle reach, means to support said third reach, and means for securing the ends of said 20 separate piece of rope to the piece forming the loop and at opposite sides of the tightening means so that the third reach may be tightened or slackened simultaneously with the other reaches and so that it travels in the same direction as the clothes carrying reach, the third reach serving as a guard to keep the clothes from lying on the idle reach when the clothes become lodged on the pulley line.

10. In a pulley clothes line, the combination of a single piece of rope, means to connect the ends of said rope to form a loop, pulleys, one at a clothes attaching station, and one remote from said station to elongate the loop to form two reaches to travel in opposite directions, said reaches being disposed one above the other, the lower reach constituting a clothes carrying reach, the upper reach being an idle reach, the connecting means being also effective to tighten or slacken said reaches, a separate piece of rope to form a third reach, said third reach being coextensive with the other reaches and located above the idle reach, means to support said third reach, means for securing the ends of said separate piece of rope to the piece forming the loop and at opposite sides of the connecting means so that the third reach may be tightened or slackened simultaneously with the other reaches and so that it travels in the same direction as the clothes carrying reach, the third

reach which is located above said loop serving as a guard to keep the clothes from lying on said upper reach when the clothes become wrapped about the pulley line, and a device cooperating with all of said reaches to keep them definitely spaced, said device having means to grip the lower reach of said loop to travel with said lower reach, and means on said device to facilitate freedom of transit of said device on the upper reach of the loop.

11. In a pulley clothes line, the combination of a single piece of rope, means to connect the ends of said rope to form a loop, pulleys, one at a clothes attaching station, and one remote from said station, said pulleys supporting the loop to provide two reaches arranged one above the other and to travel in opposite directions, the connecting means being also effective to tighten or slacken said reaches, a separate piece of rope to form a third reach coextensive with the other reaches, means to support said third reach under said loop, means for securing the ends of said separate piece of rope to the piece forming the loop and at opposite sides of the tightening means so that the third reach may be tightened or slackened simultaneously with the other reaches, said reaches being arranged in superposed relation in the same plane and constituting two outer reaches and an intermediate reach, the upper, outer reach and the intermediate reach being provided by said loop, said upper reach and said third reach traveling in the same direction and opposite to the direction of travel of the lower reach of said loop, said third reach serving as a clothes supporting reach, said upper reach of the loop serving as a guard reach to keep the clothes from lying on the intermediate reach when the clothes become lodged upon the pulley line.

12. The combination of a pulley clothes line in the form of a loop and having two reaches, namely a clothes carrying reach and an idle reach formed of a single piece of rope, the idle reach being located above the clothes carrying reach said reaches being arranged to travel in opposite directions, two pulleys to guide said reaches, one of said pulleys being located near a clothes attaching station, the other pulley being located remote from said station, a separate piece of material to form a third reach to serve as a guard reach located above the idle reach, both ends of the third reach being secured to said loop, the major portion of the piece to form said guard reach extending along said loop, a separate pulley located at the station end of the pulley line to support and guide one end of said guard reach, a device secured to the clothes carrying reach to guide the other end of the guard reach, said device including means to guide it on the idle reach, and means to attach said device to the guard reach, the reaches being arranged with reference to each other to form two outer reaches traveling in the same direction, and an intermediate reach traveling in a direction opposite to the direction of travel of the outer reaches, and a detachable holder attached to one of the outer reaches to travel therewith and to keep all of said reaches definitely spaced.

13. In a pulley clothes line, the combination of a piece of rope forming an elongated loop constituting two reaches, namely an upper idle reach, and a lower clothes carrying reach, pulleys, one at a clothes attaching station, and one remote from said station to support the loop so that the reaches travel in opposite directions, a

third reach located above the idle reach and connected to said loop, a separate pulley located above the pulley at said station to support one end of said third reach, a device supported by and secured to the clothes carrying reach to support the other end of the third reach above the idle reach, means to guide said device on the idle reach, means extending from said device to engage the clothes carrying reach to counteract a pull exerted on said device by said third reach and thus maintain said device in a substantially vertical position on the pulley line, the reaches being disposed with reference to each other to form two outer reaches traveling in the same direction and an intermediate reach traveling in a direction opposite to the direction of travel of the outer reaches, and a holder attached to one of the outer reaches to travel therewith and to keep all of said reaches definitely spaced.

14. In a pulley clothes line, the combination of an elongated loop of rope having two parallel reaches, pulleys, one at each end of said loop, to guide said reaches in a vertical plane to travel in opposite directions, separate means, means to support said separate means to form a third reach coextensive with the other two reaches and in the same plane as the other two reaches, said reaches being arranged with respect to each other so that one of the loop reaches and the third reach from outer reaches, the other loop reach being arranged intermediately between said outer reaches, the supporting means including means to cause the third reach to travel simultaneously with and in the same direction as the other outer reach, the lowermost outer reach serving as a clothes carrying reach, the uppermost outer reach serving as a guard reach to prevent the articles of clothes when blown over the pulley line from lying on the intermediate reach, and a holder detachably secured to one of the outer reaches to keep all of the reaches definitely spaced to prevent them from moving towards or away from each other.

15. In a pulley clothes line, the combination of a piece of rope in the form of an elongated loop constituting an upper reach and a lower reach, pulleys, one at a clothes attaching station, and one remote from said station, said pulleys supporting the rope so that the reaches travel in opposite directions, a third reach connected to said loop, a separate pulley at said station to support one end of said third reach, a device supported by and secured to one of the loop reaches to support the other end of the third reach, means to guide said device on the other one of the loop reaches, said reaches being arranged above each other, means extending from said device to engage the loop reach to which said device is secured to counteract a pull exerted on one end of said device by said third reach, and thus maintain said device in a substantially vertical position on the pulley line, means to tighten or slacken all of said reaches, and a holder to keep all of said reaches definitely spaced from each other, said holder having means to secure it to one of the outer reaches, means to engage the other outer reach and to permit a slight relative movement between the last mentioned reach and said holder during a tightening or slackening operation of the line, and intermediate means to facilitate freedom of transit of said holder on the intermediate reach.

16. In a pulley clothes line the combination of an elongated loop having two coextensive reaches, supporting devices for said loop one at

each end thereof by which they are guided to travel simultaneously in opposite directions in a vertical plane, means extendible along the loop reaches to establish a third reach, means including a stationary device and a movable device to guide the extendible means in the same vertical plane, said movable device being secured to one of the loop reaches, means on the movable device to guide it for movement back and forth on the other one of the loop reaches, said movable device being effective as it travels back and forth to vary the length of the extendible means, and a detachable device attachable to the clothes line at a position between the stationary device and the movable device to keep all of the reaches definitely spaced.

17. In a pulley clothes line, the combination of a single piece of rope forming a loop, two pulleys to support said loop to elongate it and thus produce two coextensive reaches to travel in opposite directions, one of said pulleys being located at a clothes attaching station, the other pulley being remote from said station, another piece of rope connected to said loop, means to support the last mentioned piece of rope to form a third reach, the supporting means including a device attached to one of the loop reaches, said third reach being short at the beginning of a clothes attaching operation, said devices being effective to increase the length of the third reach as the attaching of the clothes to said line progresses, all of the reaches being arranged in a vertical plane and providing two outer reaches traveling in the same direction and an intermediate reach traveling in a direction opposite to the direction of travel of the outer reaches, one of the outer reaches serving as a clothes attaching reach, the other outer reach serving as a guard reach to keep the clothes when blown over the line from lying on the intermediate reach, and one or more holders which may be attached to the line as the length of the third reach increases to engage all of said reaches to keep them definitely spaced.

18. In a pulley clothes line, the combination of a single piece of rope forming a loop, two pulleys to support said loop to elongate it and thus produce two coextensive reaches to travel in opposite directions, one of said pulleys being located at a clothes attaching station, the other pulley being remote from said station, another piece of rope connected to said loop, means to support the last mentioned piece of rope to form a third reach, the supporting means including stationary means at said station to guide one end of the third reach, and means on said loop to travel with one of its reaches to guide the other end of the third reach, said third reach extending from said stationary means to the traveling means, the traveling means being near the stationary means at the beginning of a clothes attaching operation, and the third reach being then short, the traveling means being effective to increase the length of the third reach while it moves away from the stationary means as the attaching of the clothes to said line progresses, all of the reaches being arranged in a vertical plane and to provide two outer reaches to travel in the same direction and an intermediate reach to travel in a direction opposite to the direction of travel of the outer reaches, one of the outer reaches serving as a clothes attaching reach, the other outer reach serving as a guard reach to keep the clothes when blown over the line from lying on the intermediate reach, and one or

more detachable holders which may be attached to the line to engage all of said reaches as the length of the third reach increases to keep them definitely spaced.

- 5 19. In a pulley clothes line, the combination of a piece of rope in the form of an elongated loop to provide two coextensive reaches, pulleys to support said loop so that the two reaches may travel simultaneously in opposite directions in a vertical plane, a separate piece of rope, and means to support the latter in said vertical plane and close to the loop reaches so as to provide a third reach, the supporting means including a holder, means at one end of the holder to grip one of the loop reaches, means on the holder cooperating with the other loop reach to guide the holder thereby, means on the opposite end of the holder for connecting one end of the separate piece of rope to said holder, and an arm extending from said holder into engagement with the loop reach which is gripped by said holder, said arm counteracting a pull exerted on one end of the holder by the third reach and thus maintaining the holder substantially vertical to the pulley line.
- 10 20. In a pulley clothes line, the combination of a piece of rope in the form of an elongated loop to provide two coextensive reaches, pulleys to support said loop so that the two reaches may travel simultaneously in opposite directions in a vertical plane, a separate piece of rope, means to support the latter in said vertical plane and close to the loop reaches so as to provide a third reach, the supporting means including a vertically disposed holder, means at one end of the holder to grip one of the loop reaches, means on the holder cooperating with the other loop reach to guide the holder thereby, means on the opposite end of the holder to grip the third reach, a portion
- 15 25 30 35 40 45 50 55 60 65 70
- of the third reach extending from the last mentioned gripping means to the reach engaged by the first mentioned gripping means, and means to attach the end of said portion of the third reach to the reach to which it extends, said portion of the third reach being effective to maintain the holder substantially vertical to the line against the tendency of the third reach to move the holder from its vertical position.
21. In a pulley clothes line, the combination of a piece of rope in the form of an elongated loop to provide two coextensive reaches, pulleys to support said loop so that the two reaches may travel simultaneously in opposite directions in a vertical plane, one of said pulleys being located at a clothes attaching station, the other pulley being located remote from said station, a separate piece of rope, means to support the latter in said vertical plane close to the loop reaches to provide a third reach, said means including a pulley at the clothes attaching station, and a holder supported on and attached to one of the loop reaches, a clamp for attaching one end of the separate piece of rope to the other loop reach, a detachable holder connected to the same reach to which the other holder is attached, means on each holder to guide it on the reach to which the clamp is attached, and means on each holder to assist in facilitating unobstructed passage of said clamp past said holders.
22. In a pulley clothes line, the combination of an elongated loop, pulleys, one at each end of said loop to support the latter and thus provide a clothes carrying reach and an idle reach arranged above the clothes carrying reach, said reaches to travel simultaneously in opposite di-

rections, extendable means, and means to support the extendable means above the idle reach to provide a guard reach to travel in the same direction as the clothes carrying reach and prevent articles of clothes when blown over the line from lying on the idle reach, the supporting means including a device attached to the clothes carrying reach to vary the length of the guard reach to correspond substantially with the length of the active portion of the clothes carrying reach.

23. In a pulley clothes line, the combination of an elongated loop, pulleys, one at each end of said loop to support the latter and thus provide an upper reach and a lower reach to travel simultaneously in opposite directions, extendable means, and means to support the extendable means under said loop to provide a clothes carrying reach, the supporting means including a device attached to said upper reach to cause the clothes carrying reach to travel in the same direction as said upper reach and vary the length of the clothes carrying reach as its need is varied in accordance with the number of articles of clothes to be supported thereby, the upper reach of said loop serving as a guard reach to prevent the clothes when blown over the line from lying on the lower loop reach.

24. In a pulley clothes line, the combination of an elongated loop, pulleys, one at each end of said loop to support the latter to provide two coextensive reaches to travel simultaneously in opposite directions, means extendable along said loop to provide a third reach, means to support the extendable means close to the loop to guide and support one end of the third reach and whereby the length of the third reach may be varied in accordance with the number of articles of clothes to be carried by the pulley line, the reaches being arranged above each other and forming an upper outer reach, a lower outer reach, and an intermediate reach, the lower outer reach being effective to serve as a clothes carrying reach, the upper outer reach being effective to serve as a guard reach, the two outer reaches traveling simultaneously in the same direction, the supporting means for the extendable means including a device attached to the outer reach formed by the loop, and a holder attachable to the line to travel with the two outer reaches and keep all of the reaches properly spaced from each other.
